UNITED STATES PATENT OFFICE.

STEPHEN C. COLLINS, OF OREGON, MISSOURI.

IMPROVEMENT IN APPLE-CORERS.

Specification forming part of Letters Patent No. 120,857, dated November 14, 1871.

To all whom it may concern:

Be it known that I, STEPHEN C. COLLINS, of Oregon, in the county of Holt and State of Missouri, have invented a new and useful Improvement in Apple-Corer; and I do hereby declare that the following is a full, clear, and exact description thereof, which will enable others skilled in the art to make and use the same, reference being had to the accompanying drawing forming part of this specification.

Figure 1 represents a side view of my improved apple-corer. Fig. 2 is an end view of the same.

Similar letters of reference indicate corresponding parts.

This invention relates to a new, simple tool for coring apples, that consists only of a handle and a trough-shaped conical cutting-blade, which is adapted to core apples of larger or smaller size.

The handle A is made of wood or other mate-

rial. B is the cutting-blade, made trough-shaped and attached to or formed on a ferrule, a, that is slipped over the end of the handle. The straight edges b b of the blade B are sharpened as well as its end c, so it will easily enter an apple and cut out its core when turned therein. The blade, being smaller at its end than near the handle, will, by being put through an apple to a greater or less depth, cut out a larger or smaller core, as may be desired, and in accordance with the size of apple to be cored.

Having thus described my invention, I claim as new and desire to secure by Letters Patent—

The apple-corer, consisting of the handle A and trough-shaped conical blade B, substantially as herein shown and described.

STEPHEN C. COLLINS.
